UNITED STATES PATENT OFFICE.

WILLIAM S. KINSLEY, OF READING, MASSACHUSETTS, ASSIGNOR TO THE RUSSELL COMPANY, OF BOSTON, MASSACHUSETTS, A CORPORATION OF MASSACHUSETTS.

CLEANER FOR FIBROUS STOCK AND METHOD OF CLEANING FIBROUS STOCK.

Application filed January 5, 1920. Serial No. 349,509.

To all whom it may concern:

Be it known that I, WILLIAM S. KINSLEY, a citizen of the United States, and a resident of Reading, in the county of Middlesex and State of Massachusetts, have invented an Improvement in Cleaners for Fibrous Stock and Methods of Cleaning Fibrous Stock, of which the following description, in connection with the accompanying drawings, is a specification, like characters on the drawings representing like parts.

This invention pertains to improvements in cleaners for fibrous stock, methods of cleaning such stock, and more particularly, though not exclusively, to improvements in dusters for and methods of cleaning wool.

In the drawings, which show an illustrative embodiment of a preferred form of my invention:—

20 Fig. 1 is a side elevation of a preferred form of duster with its cooperating feeding device; and

25 Fig. 2 is a sectional elevation through a portion of the feeding mechanism, through the more important portions of the dusting mechanism, showing details of a preferred embodiment of my invention selected for illustrative purposes.

30 In the drawings I have shown a feeder which preferably includes a hopper indicated in its entirety at 4 having in one portion at the bottom thereof a slowly travelling conveyor 5 for conveying the stock in the direction of the spiked apron or elevator 6, which may resemble somewhat the usual Bramwell feeder, being provided with a rotary doctor 7 for knocking off from the spiked elevator any large lumps of stock which may be elevated thereby, and with a 35 clearer 8, which assists in removing from the spiked elevator the stock elevated thereby which is to be fed to the duster.

35 The apron 6 is located in the hopper portion 4^a, this portion (as indicated in Fig. 1) 45 abutting on the line 4^b the portion of the hopper containing the conveyor 5. The hopper portions 4 and 4^a are separable on the line 4^b so that the portion 4^a may be assembled complete with the apron 6, the portion 4 may be assembled complete with the conveyor 5, and the hopper portions 4 and 4^a then placed in proper relation to each other and bolted or otherwise secured together. The separability of the hopper on the line 4^b is also of advantage in that, by

separating these portions of the hopper, ready access to the apron 6 or conveyor 5 is afforded for replacement or repairs.

50 The feeder before-described preferably deposits the material in a hopper 9 communicating with a duster which preferably includes a casing fitting relatively closely about a rapidly rotated dusting element 10 having pins or other projections thereon and adapted to beat the material in the casing so that the dust may pass out through a screen 11. The duster is preferably provided with a discharge door 12 and a supply door 13, preferably operated by automatic mechanism hereinafter more fully described.

55 The machine may conveniently be driven by a pulley on the beater shaft 14, and means may be provided on said shaft for driving the belts 15 and 16 supplying power to the doctor 7 and clearer 8.

60 I have found it advantageous to provide at one end of the shaft 14 a worm 17 meshing with a worm gear 18 on a shaft 19, which may conveniently supply power for driving the conveyor 5 and elevator 6. I 65 preferably mount on the shaft 19 means for automatically controlling the discharge door 12 and supply door 13 of the duster, and in the embodiment of my invention herein shown, this means takes the form of the cam 20 adapted to rock a bell crank 21, one end of which is coupled by a connecting link 22 with a lever 23 secured to the shaft on which the discharge door 12 is pivoted. 70 This cam operates the opening of the door, the closing thereof being gravity-actuated, the weight of the door preferably being supplemented by a counterweight 24. To control the opening and closing of the supply door, I preferably provide a cam 25 on the shaft 19 adapted to rock a bell crank lever 26 connected by a link 27 to a lever 28 which in turn is connected to the supply door 13. The cam preferably actuates opening of the door, and the closing thereof is preferably yieldingly actuated as by a weight 29, which may be supplemented by a spring 30 on the connecting link 27.

75 The timing of the door operating parts is preferably such that the supply door 13 will be closed whenever the discharge door 12 is open, so that at no time can material pass through the duster without having been 80 dusted to a considerable extent.

While for some purposes and for some grades of stock it may be better to supply the material in batches to the duster, I have found that in many instances it is preferable 5 to provide what may be termed an intermittent, gradual supply of material thereto. I believe that the material which is close to the screen 11 is subjected to greater dusting action than the material which is further removed from the screen 11. I have found that the material which is last introduced into the duster tends to remain adjacent the periphery of the duster, and hence to remain 10 in closer proximity to the screen 11 and therefore to be very thoroughly cleaned.

Where a batch of material is introduced substantially as a unit, some of the material will not have as good an opportunity as other portions thereof to be dusted in those 20 portions of the beater adjacent the periphery thereof. I prefer, therefore, to so shape the door operating cams, that the supply door 13 will remain open a very substantial portion of the time during which the discharge door 12 remains closed. The feeder including the elevator 6 and cooperating parts operates continuously so that, during the period when the discharge door is open and the supply door closed, a comparatively 30 small batch of material will accumulate on the top of the supply door 13 which will fall as a very small batch into the duster as soon as the discharge door 12 is open and the supply door 13 slid to the left by the operating mechanism. After this opening of the supply door 13, the material will be fed to the duster as discharged from the feeder, and the material as it enters will be progressively subjected to the greatest cleansing action 40 adjacent the periphery of the duster. As clearly appears from Fig. 2, the casing of the duster preferably fits relatively closely to the rotating part thereof throughout substantially its entire periphery. To increase the dusting action, stationary pins 31 are provided between the rotary pins on the duster drum 10, and to facilitate discharge

the pins 31 are mounted on a rock shaft 32, which carries the lever 21, so that when the discharge door is open the pins 31 will be 50 thrown upwardly somewhat, to provide a surface which will not materially obstruct the passage of the dusted material thereby.

While I have shown and described a preferred form of one embodiment of my invention, it will be understood that major changes involving omission, substitution, alteration and reversal of parts, and even changes in the mode of operation, may be made without departing from the scope of 60 my invention, which is best defined in the following claims.

Claims:

1. A duster comprising, in combination, a rotary beating element, a casing therefor including a screen at the bottom thereof, stationary beating means at one side thereof, a discharge door at the opposite side thereof and a supply door at the top thereof.

2. Dusting apparatus comprising, in combination, a beater casing, including a supply door and a discharge door, a rotary beater having a shaft, a worm on said shaft, a worm gear meshing with said worm, and a shaft carrying said worm gear and having mounted thereon cam means for operating said supply and discharge doors.

3. A duster comprising a continuously rotating dusting element enclosed in a casing having at its periphery a screen, a supply opening and discharge opening for said casing, doors for said openings, coordinated power means for opening and closing said doors at short intervals in such manner that one is open when the other is closed, and means for feeding material to said supply door continuously and at such rate that all the material entering said casing when said supply door is open is subjected to dusting action close to said screen.

In testimony whereof, I have signed my name to this specification.

WILLIAM S. KINSLEY.
